(No Model.)

J. KÖLZER.

TELEGRAPHIC REPEATER.

No. 379,203.

Patented Mar. 6, 1888.

UNITED STATES PATENT OFFICE.

JOSEPH KÖLZER, OF DUISBURG, PRUSSIA, GERMANY.

TELEGRAPHIC REPEATER.

SPECIFICATION forming part of Letters Patent No. 379,203, dated March 6, 1883.

Application filed August 14, 1884. Renewed November 26, 1887. Serial No. 256,252. (No model.)

To all whom it may concern:

Be it known that I, JOSEPH KÖLZER, a subject of the King of Prussia, residing at Duisburg-on-the-Rhine, in the Kingdom of Prussia, 5 in the Empire of Germany, have invented new and useful Improvements in Electrical Telegraph Apparatus, of which the following is a specification.

This invention relates to telegraphic apparatus whereby messages can be transmitted from a remote station in the main line to a remote station in a branch line, from a remote station in a branch line to a remote station in the main line, and also for sending messages 15 from a station on a branch line to a home or receiving station that has been disconnected from the main line or electrical circuit, and also for transmitting messages between main lines.

20 The invention consists in polarized relays of special construction and an arrangement of circuit-closing keys, commutators, registers, and main-line and branch-line electrical circuits, whereby messages can be transmitted in the manner above briefly described, all of 25 which is more fully pointed out in the following specification and claims, and illustrated in the accompanying drawing, in which the figure is a view showing the arrangement of parts for transmitting messages from stations in a branch line to stations in a main line, and vice versa.

In the drawing, the letters R' R² indicate the two Morse relays. S' S² are the registers; U', U², and U³, the commutators; T' T², the finger-keys; G' G², the galvanometers; B', the local battery connected with the branch line, and B² is the battery connected with the main line.

O W is the main-line circuit, and N the 40 branch-line circuit.

The armature-lever C of the relay R' in the circuit of the branch line N is provided with an extension, C', having thereon a head-piece, a, which projects downward and is bent upward so as to form a hook, on the end of which is an upwardly-extending contact, k, which may be formed by a small metal screw.

i is an elastic steel spring or arm, which is secured by small screws to the armature-lever C, but is separated therefrom by a plate or layer, o, of insulating material. When in its normal position, the spring-arm bears with its

free end against the contact k of the head-piece a, so that the circuit is closed.

l l' are the contacts or stops. 55

j is a button or stud which projects from the insulating layer o and forms a stop for the spring-arm i, so that its entire surface will not bear upon the insulating layer.

The spring-arm is connected, by a spiral 60 spring, g, to a binding-post, h, insulated from the relay R', the said spiral spring being made of very thin wire and very elastic in order that it can participate in the movements of the armature-lever C without exerting any apprecia- 65 ble force upon the same.

The armature-lever n n' of the relay R², which is introduced in the main-line circuit, is similarly constructed and arranged as lever C of relay R'. In its normal position the armature-lever C is against stop l, and armature-lever n n' is against stop l', in which position they are respectively drawn by springs z z'. On this armature-lever is secured a metallic contact-plate, m, which is separated from the lever by an insulating-plate, e. This metallic contact-plate conducts the current departing for the circuit N, which enters over the contact d', after the falling back of the armature, directly through spring g', which is attached 80 to the plate by screw s, and to a screw, h', and the current does not pass through relay R', but is led directly to the branch-line circuit N. 75

The finger-key T' is provided with a broken working contact-plate, r' r², as shown, of which 85 the smaller section at the left is connected with the contact d' of relay R², and the longer section on the right, being the one with which the key comes in contact when depressed, is connected with one pole of the battery B². 90

The back plate of commutator U³ is broken and may be electrically joined by means of a plug.

For transmitting messages from the main line O W to the branch line N, and vice versa, 95 the holes 1 are plugged in the commutators U' U² U³ and in the finger-key T'. The course of the current in the main line from O to W is now as follows: To the galvanometer G², the register S², the battery B', the commutator U², the relay R², through the following parts of relay R', viz: binding-post h, spring g, spring-arm i, contact k, armature-lever C' C. From 100 the latter the current passes to commutator

U^2 , over plugged hole 1, to finger-keys T^2 , and from thence to the point W of the main line. When the circuit is established, as just described, the armature-lever of the relay R^2 and 5 the register S^2 are attracted by the respective magnets, and the lever of relay R^2 is held against the stop or contact d , as shown in Fig. 1.

The course of the current in the branch line N is as follows: From the point of the wire 10 through the galvanometer G' , the finger-keys T' , the commutator U' , (over plugged hole 1,) coils of relay R' , the commutator U^3 , (middle plate,) the armature-lever $n n'$ of the relay R^2 , the contact or stop d , commutator U^3 , front plate, 15 and then to the ground. If now the main-line circuit is broken by depressing a finger-key, the writing apparatus S^2 and the relay R^2 become devitalized, and the armature-lever $n n'$ of the latter falls against back-stop d' , so that communication with the ground is interrupted at 20 d , and the circuit of battery B^2 is closed, as follows: One pole of this battery is connected with the earth, causing the current to pass from the other pole to the finger-key T' through the 25 plugged hole r , and from thence to the relay R^2 , through the medium of stop d' , contact-plate m , spring g' , and binding-screw h' , to commutator U^3 , over plugged hole 1 therein to commutator U' , over plugged hole 1 to finger- 30 key T' through the body of the key to the back plate to galvanometer G' , and from thence to the branch line N , to actuate the register at a distant station. The current cannot deviate from commutator U' to the relay R^2 to the 35 middle plate of the commutator U^3 , through armature-lever $n n'$ to the stop or contact d to the earth, because the said armature-lever $n n'$ is in contact with stop d' as long as a departing current is circulating in the wires, and the 40 circuit to the earth is consequently interrupted.

If the remote station of the branch-circuit N sends a current into the circuit, the current passes through armature-lever $n n'$ and stop d 45 to the ground, the armature-lever C of the relay R' is attracted, and the arm i of said lever is brought into contact with stop or contact l' , so that the local current, from contact l' , the battery B^2 , commutator U^2 , relay R^2 , binding-screw h , spring g , and spring-arm i , is closed. The armature-lever C being attracted, as before stated, by the relay-magnets, the main-line circuit is broken, since the spring-arm i is thrown out of contact with contact k .

55 Since the armature-lever $n n'$ of the relay R^2 remains in contact with stop d' , a disturbing current cannot enter into the branch-line circuit N , as the local current of battery B^2 (passing from stop or contact l' to spring-arm i , in 60 the manner before described) is closed before the main circuit $O W$ is broken, and the communication with the ground is always maintained at stop d . If the current ceases in the circuit N , the armature-lever C falls away from 65 contact l' . The spring-arm i remains in contact with stop or contact l' until it is engaged

by the contact k , whence it closes the main-line circuit $O W$, after which the local current from battery B^2 is broken. An uninterrupted circuit is maintained through the bobbins of 70 relay R^2 during the entire period in which the branch circuit is in operation, because the local current is always closed previous to the breaking of the main-line current, and the main-line current is closed before the local 75 current is broken. The armature-lever $n n'$ is consequently always attracted and in contact with contact or stop d , by which connection with the ground is always maintained on one side, and on the other no disturbing current 80 can enter the branch-line circuit N .

Instead of the relays $R' R^2$, writing apparatus can be employed.

For transmitting messages when the branch-line circuit is separated or disconnected from 85 the main-line circuit $O W$, the plugs of commutators U^2 and U^3 are removed from the holes 1 and inserted into holes 2 of said commutators. The course of the current in the main line from O to W is now as follows, viz: 90 from wire O to galvanometer G^2 , to writing apparatus S^2 , battery B^2 to commutator U^2 , over plugged hole 2 therein to finger-key T^2 , and from the back plate of key-plate to W . The armature-lever of the relay R^2 falls from 95 stop d , since no current now circulates through the bobbins, because the plug of the commutator U^3 has been removed to hole 1 therein, and the circuit is thus broken for the departing current. The arriving current of the 100 branch circuit, on the contrary, since its connection with the ground is also broken at stop d , flows through the commutator U^3 over 105 plugged hole therein to the ground.

If a remote station on the branch line N 110 calls, the relay R' is put in motion and the local current from battery B^2 is closed. The relay R^2 is also put in action, and in this case acts as an apparatus intercalated in the branch line. It is now possible to hear when remote 115 stations of the circuit N call stations of the circuit $O W$, and then to establish the communications between the two circuits, so that the stations may reach one another. The branch line N is put into communication with 120 the register S' when the two relays are switched from the circuit. If it is found necessary for any reason to separate the circuit N from the main circuit $O W$ and from the transmitting system, the plugs of the commutator U' and of 125 the finger-key T' may be taken out of hole 1 and inserted into hole 2. The system of transmission and the circuit $O W$ are thus thrown out of the circuit and the register S' is switched into the circuit. The current in the branch 130 line now flows as follows, viz: From point N to galvanometer G' , to commutator U' , over plugged hole 2 therein to the register S' , and from thence it passes to the ground.

When the finger-key T' is depressed, the departing current of the branch line passes from battery B' to finger-key T' , over plugged hole 2

therein to galvanometer G' , to wire N of the branch circuit. The branch circuit has become in this case an independent circuit.

What I claim as new, and desire to secure by Letters Patent, is—

1. In a telegraph apparatus for transmitting messages through a main line and branch line, and vice versa, the combination of a relay, R' , having its armature-lever provided with an extension, C' , a contact, k , an insulating-strip, o , spring-arm i , yielding conductor g , connected with said spring-wire i , and binding-post h , the stops l l' , the relay R^2 , having its armature provided with an extension, n' , a contact-plate, m , insulating layer e , yielding conductor g' , connected with the contact-plate m , and binding-post h' , the stops d d' , line connection with the relays R' R^2 for main and branch electrical circuits, suitable batteries B' B^2 , finger-keys T' T^2 , and commu-

tators U' U^2 U^3 , all substantially as shown and described.

2. In a telegraph apparatus, the relay R^2 , having its armature-lever provided with an extension, n' , a contact-plate mounted on the extension and insulated from the armature-lever, a yielding electrical conductor, g' , connected with the contact-plate, and a binding-post, h' , on the base of the relay, with the main and branch electrical circuits, batteries B' B^2 , finger-keys T' T^2 , relay R' , and commutators U' U^2 U^3 , all arranged substantially as shown and described.

In testimony whereof I have signed my name to this specification in the presence of two sub-
scribing witnesses.

JOSEPH KÖLZER.
